ABSTRACT: A rigid body means defines a slot extending longitudinally thereof for receiving a metal joint. A first cam means is supported by the body means at one side of the slot and defines a continuous cam surface extending longitudinally of the cam means, said surface having portions of different slope disposed at points spaced longitudinally thereof. This first cam means includes a sharp entry edge. A second cam means is supported by the body means in spaced aligned relationship to the first body means and includes a sharp entry edge. The second cam means is mounted on a rotatable shaft having an operating handle secured thereto which is engageable with a retainer pin received in a hole in the body means to limit rotation of the shaft which carries the second cam means.

METAL-JOINT-OPENING DEVICE

BACKGROUND OF THE INVENTION

The present invention relates to a metal-joint-opening device which is particularly adapted to open a standing metal seam as formed between adjacent metal roof panels. Such seams are formed by mechanisms as shown, for example, in U.S. Pat. No. 3,120,828, which is adapted to form either single or double seams.

It is desirable from time to time to repair damaged metal roof panels which have been secured to one another by such a standing seam. In order to do so, it is necessary to open the seam, remove the damaged panel and then replace it with a new panel.

In the past, such seams have been opened with handtools such as by driving a wedge along the seam with a hammer, or by cutting the metal out. Such operations require a considerable amount of time, labor and operator's skill and, furthermore, the damage of the flanges in adjacent panels has usually been so severe that reseaming of a new replacement panel could not be accomplished in a satisfactory manner.

SUMMARY OF THE INVENTION

In the present invention, a rigid body means is provided with an elongated slot extending longitudinally thereof for receiving a metal joint, such as a roof seam, which is to be opened. Suitable means is provided for moving the body means along a metal joint. A driving abutment is rigidly secured to the body means and extends laterally thereof, this driving abutment being adapted to be engaged by a hammer so as to enable the body means to be manually driven along an associated metal joint. A connecting means in the form of a pivotally mounted hook is also provided, this hook being adapted to engage a suitable driving mechanism. The body means can be pulled along a metal joint by a machine, such as is shown in the aforementioned U.S. patent in a direction opposite to that in which the machine shown in the patent moves in producing the seam. The device of the present invention may also be self-powered if so desired.

The present invention includes a first elongated cam means supported on the body means at one side of the slot. This cam means has a sharp entry edge and is provided with a continuous cam surface extending longitudinally of the cam means, this cam surface having portions of different slope disposed at points spaced longitudinally therealong so as to progressively cam a formed metal joint toward an open position as the device moves along the joint.

A second cam means is provided in spaced aligned relationship to the first cam means and includes a sharp entry edge. The second cam means is mounted on a rotatable shaft which has an operating handle for rotating the second cam means into position. A retainer pin is received in a hole in the body means and is engageable with the handle to limit rotation of the shaft on which the second cam means is mounted.

As the device of the present invention is moved along a metal joint, the joint is progressively cammed toward open position by the first cam means, and the second cam means then serves to complete the unfolding and straightening of the metal of the joint. The second cam means enters the joint only after the first cam means has opened the joint to a predetermined extent.

In actual use, the first cam means may be more readily inserted into a metal joint to be opened, if the first inch or so of the joint is initially partially manually opened by driving a wedge into the joint.

Initial tests of a model of the device of the present invention have proved successful with a minimum of adjustment. A metal joint has been completely taken apart and then reseamed with no loss in joint efficiency except for some damage to the paint on the joint. Additionally, the device of the present invention works equally well when metal clips used to hold the panels to the roof structure were included in the seam joints.

BRIEF DESCRIPTION OF THE DRAWINGS

- FIG. 1 is a top perspective view of a metal-joint-opening device according to the present invention;
- 5 FIG. 2 is a top perspective exploded view illustrating the first cam means of the device and a double-seamed metal joint;
- 10 FIG. 3 is an end view of the far end of the structure shown in FIG. 1;
- 15 FIG. 4 is a sectional view taken substantially along line 4-4 of FIG. 1, looking in the direction of the arrows;
- 20 FIG. 5 is a top view of the far end of the structure shown in FIG. 1;
- 25 FIG. 6 is a top perspective view illustrating the second cam means as well as the shaft upon which it is mounted and the associated operating handle;
- 30 FIGS. 7, 8 and 9 are sectional views through a metal joint illustrating successive steps in opening a formed metal joint seam when utilizing a device according to the present invention.

- DESCRIPTION OF THE PREFERRED EMBODIMENT
- Referring now to the drawings wherein like reference characters designate corresponding parts throughout the several views, the metal-joint-opening device of the present invention includes a body means indicated generally by reference numeral 10, including a plate 12 defining a top wall portion of the body means and having a cutout portion 14. Plate 12, as well as the remaining components of the body means, is formed of a rigid heavy-duty material such as steel or the like. A pair of plates 16 and 18 define sidewall portions of the body means and extend substantially perpendicular to the plate 12. Plates 16 and 18 are secured to plate 12 by means of suitable fasteners such as Allen head capscrews 20 which are threaded within suitable aligned threaded holes provided in plates 12, 16 and 18. In addition to these screws, plates 16 and 18 may be welded to plate 12 to provide a rigid construction.
- A pair of bottom plates 30 and 32 are secured to and extend laterally from the lower edges of plates 16 and 18. Plates 30 and 32 are secured in place by means of suitable fasteners such as Allen head capscrews 34 extending through aligned threaded holes provided in members 30 and 16 and members 32 and 18 respectively. Such an arrangement allows the plates 30 and 32 to be removed, if desired, to facilitate cleaning, etc.
- It will be noted, as seen in FIGS. 1, 3 and 4, that the side edges of plates 30 and 32 are spaced apart to define a slot 38 which extends longitudinally throughout the length of the device for receiving a metal joint to be opened.
- Means is provided for moving the device along a joint to be opened, this means including a driving abutment 40 which is, for example, a sturdy piece of steel having rounded end portions 42 adapted to be engaged by a hammer or the like for driving the body means along a seam. Driving abutment 40 is rigidly secured to plate 10 as by welding.
- A further means for moving the device along a joint includes a pair of spaced ears 50 in the form of metal plates rigidly secured as by welding to the upper surface of plate 12. A connecting member 52 has one end thereof received between ears 50 and pivotally connected therewith by means of a bolt 54 extending through aligned holes provided in ears 50 and member 52 and having a nut 56 threaded on the end thereof. The outer end of member 52 defines a hook portion 58 adapted to receive the end of a cable or the like indicated by phantom line 60 which in turn may be connected to any suitable driving mechanism such as a machine shown in the aforementioned U.S. patent.
- Referring now to FIG. 2 of the drawings, a typical double-seam metal joint J is shown in cross section, it being the objective of the present invention to open up such a formed metal joint. Also shown in FIG. 2 is the first cam means 70 of the present invention which is secured to and extends upwardly from plate 30.
- Cam means 70 includes a sharp entry edge 72 which extends substantially perpendicular to the upper surface of plate

30 and which facilitates entry of the cam means into a joint to be opened. The base portion of the cam means adjacent the upper surface of plate 30 flares laterally outwardly along a line 74 to a point 76 so that this portion of the base part of the cam means is of increasing thickness adjacent the upper surface of plate 30. The base portion of the cam means remains of constant thickness throughout the remainder of the length of the cam means from point 76 to the opposite end of the cam means.

The cam means defines a cam surface 80 which is continuous extends throughout the length of the cam means. This cam surface has portions of different slope disposed at spaced points longitudinally therealong, the surface continuously changing slope in a longitudinal direction at a rate of approximately 15° change in slope for each inch of length of the cam means whereby the slope of cam surface 80 is adapted to change through an angle of approximately 180° in 12 inches of length of the cam means. The slope of cam surface 80 changes from an approximately vertical position at entry edge 72 to a 45° angle at point 76. The slope of the cam surface continues to change until it reaches a point 82 wherein the slope has changed from approximately 0° at entry edge 72 to 45° at point 76 to approximately 180° at point 82.

Cam means 70 is provided with a cutout portion 84 at the far end thereof as seen in FIG. 2, and a pair of cylindrical holes 86 and 88 extend through the cam means for a purpose hereinafter described.

Referring now to FIGS. 3, 5 and 6, the second cam means comprises a relatively thin platelike member 100 having a sharp entry edge 102 which is filed to provide a knife edge to facilitate entry of this second cam means into a metal joint. The second cam means includes a sloping upper surface 104 for moving portions of the metal joint into a desired position.

Cam member 100 is fixed to the outer end of a shaft 110 which is rotatably journaled within the aforementioned hole 86 extending through cam means 70. An operating handle 112 has a threaded end portion which is threaded into a suitable hole provided in the opposite end of shaft 110 for securing the operating handle to the shaft. Cam member 100 is accordingly adapted to be rotated into and out of the operative position shown in FIGS. 1, 3 and 5 wherein it is adapted to enter and open a metal joint.

In order to hold the second cam means in operative position, a retainer member in the form of a cylindrical retainer pin 120 is provided, this retainer pin being received in the aforementioned hole 88 provided through cam means 70.

In the operative position of the second cam means, handle 112 engages retainer pin 120 to prevent further rotation of handle 112 in a clockwise direction as seen in FIG. 1 under the influence of a metal joint in engagement with cam member 100.

Retainer pin 120 has a cotter pin 124 extending through a suitable hole provided therein. A flexible elongated retainer member 126 in the form of a chain has one end thereof secured to cotter pin 124, the opposite end of chain 126 being fixedly secured as by tack welding at 128 to plate 12 of the body means. Chain 126 will insure that retainer pin 120 will remain operatively connected with the body means at all times to prevent loss thereof.

Referring now to FIG. 7, a section is shown through a formed metal joint to be opened. The sharpened entry edge of the first cam means is initially inserted at the point indicated by reference character 130, whereupon the opening device is moved longitudinally of the joint.

FIG. 8 indicates the condition of the joint after the first cam means has moved completely past a point on the joint. At this stage of the operation, the sharp entry edge of the second cam means enters the joint at the point indicated by reference character 132.

FIG. 9 illustrates the condition of the seam after the second cam means has passed a certain point on the seam. It is apparent that the seam has been completely opened whereupon the adjacent panels indicated by reference characters P can be readily separated from one another.

Referring now to FIG. 5, the undersurface of plate 12 of the body means is provided with slot means including a first portion 140 extending substantially parallel with the slot 38 defined by the body means. Portion 140 of the slot means intersects a further portion 142 of the slot means, portion 142 extending obliquely to portion 140. The portions 140 and 142 of the slot means are adapted to receive the upper edge portion of a seam as it is opened and passes through the body means.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equivalents, are therefore intended to be embraced by those claims.

What is claimed is:

20. A metal-joint-opening device comprising a body means defining an elongated slot for receiving a standing folded metal joint, means for moving said body means along said standing metal joint, and cam means supported on said body means in said slot at one side thereof, said cam means having portions of different slope disposed at points spaced longitudinally thereof so as to progressively cam said metal joint to unfolded open position as the body means and the cam means supported thereby are moved along the joint.
25. A device as defined in claim 1, wherein said cam means includes a continuous cam surface extending longitudinally of said cam means.
30. A device as defined in claim 2, wherein said cam surface has a substantially constant degree of change of slope thereof throughout the length of the cam surface.
35. A device as defined in claim 1, wherein said cam means has a sharp entry edge to facilitate movement of said cam means into a formed metal joint.
40. A device as defined in claim 1, including a second separate cam means disposed in aligned relationship with respect to said first-mentioned cam means.
45. A device as defined in claim 5, wherein said second cam means has a sharp entry edge to facilitate entry thereof into a formed metal joint.
50. A device as defined in claim 5, wherein said second cam means is mounted on a shaft, said shaft being rotatably supported by said body means, and an operating handle connected to said shaft.
55. A device as defined in claim 7, including a retainer pin engageable with said handle to limit rotation of said shaft.
60. A device as defined in claim 8, wherein said body means has a hole formed therein, said hole receiving a portion of said retainer pin.
65. A device as defined in claim 8, including a flexible elongated retainer member connected with said retainer pin, said retainer member being fixedly attached to said body means.
70. A device as defined in claim 1, wherein said means for moving the body means includes a driving abutment rigidly attached to said body means and extending therefrom.
75. A device as defined in claim 1, wherein said means for moving said body means includes a connecting means interconnected with said body means for connecting the body means to a driving mechanism.
80. A device as defined in claim 12, wherein said connecting means includes a hook pivotally attached to said body means.
85. A device as defined in claim 1, wherein said body means includes a top wall portion, said top wall portion having a slot means formed in the undersurface thereof for receiving a portion of a metal joint.
90. A device as defined in claim 14, wherein said slot means includes a first portion extending generally parallel with said first-mentioned slot defined by said body means and also includes a portion extending obliquely to said first portion of the slot means.
